ELECTRIC HEATING ELEMENT

Original Filed Oct. 8, 1927

INVENTOR.

S.S. Bolsinger,

BY
Geo. P. Kimmel.
ATTORNEY.

UNITED STATES PATENT OFFICE.

SAMUEL S. BOLSINGER, OF ROSEBURG, OREGON.

ELECTRIC HEATING ELEMENT.

Original application filed October 8, 1927, Serial No. 224,911. Divided and this application filed August 21, 1928. Serial No. 301,076.

This invention relates to an electric heater and is a division of my application filed October 8, 1927, Serial Number 224,911.

The primary object of the invention is to provide, in a manner as hereinafter set forth, a device for use in connection with gasoline or kerosene burners whereby the fire hazard, delay due to priming, and other objectionable features may be eliminated when it is 10 desired to light the burner.

A further object of the invention is to provide a device for the purpose above set forth which is simple in construction, inexpensive to manufacture, strong, durable, 15 compact, and which may be readily installed with respect to the fuel feed line leading to a gasoline or kerosene burner whereby the burner may be expeditiously lighted when desired.

20 Other objects and advantages of the invention will be apparent during the course of the following description.

In the accompanying drawings in which like numerals are employed to designate like 25 parts throughout the same,

Figure 1 is a side elevation of a heating element constructed in accordance with this invention, showing an adaptation of the same with respect to a fuel feed line.

30 Figure 2 is a view similar to Figure 1, showing the heating element in longitudinal section.

Figure 3 is an end elevation of the heating element, showing the feed line upon which it is mounted in section.

35 Figure 4 is a detail view of the core in longitudinal section.

In the drawings wherein for the purpose of illustration is shown an embodiment of 40 my invention, the numeral 1 designates a tubular core adapted to be mounted on a fuel line 2. The core 1 may be formed from any suitable material which is a conductor of heat and a non-conductor of electricity and is provided with a continuous 45 thread or groove 3 extending circumferentially therearound in a spiral formation to receive therein the convolutions of a nichrome wire 4, the ends of which are adapted to be connected, as indicated at 5, with a source of electrical energy, not shown. The 50 thread 3 is of a depth substantially twice the diameter of the wire 4 to permit expansion of the wire with a minimum pressure by the 55 convolutions thereof upon the core 1. The

spiral formation of the single thread 3 permits a single length of wire to be used with the convolutions thereof encircling the core 1 in spiral formation and maintained in spaced relation, thereby eliminating any 60 possibility of the convolutions crowding together. In this manner, a continuous contact is established between the wire and core and the contact is distributed evenly throughout the length of the core. 65

Mounted on the fuel line 2, adjacent the ends of the core 1, is a pair of heat confining collars or washers 6. The walls of the collars 6 are in alignment with the wall of the core 1 and the inner faces of the collars 6 70 respectively abut the respective ends of the core 1. Mounted on the assembled core 1 and collars 6 is a heat confining, tubular jacket 7, the inner diameter of which is of appropriate size to permit the jacket 7 to 75 snugly receive the core 1 and collars 6 therein. The jacket 7 is of greater length than the core 1 but of less length than the combined length of the core 1 and collars 6. In the assembled relation of the jacket 7, 80 core 1, and collars 6, the outermost portions of the latter project outwardly from the ends of the jacket 7. The wall of the jacket 7 is provided with a pair of spaced openings 8, which are respectively disposed adjacent 85 the respective ends of the thread 3, for the passage therethrough of the respective ends of the wire 4.

The jacket 7 and collars 6 may be formed of any suitable material adapted to prevent 90 or retard the heat from the convolutions of the wire 4 from passing to the outer atmosphere. It is immaterial whether or not the jacket and collars are formed of electricity 95 conducting material, except that, if such material be used, insulation of any suitable type will be required for the walls of the openings 8. At all other points the jacket 7, as well as the collars 6, are insulated from the wire 4 by the core 1. When the wire 4 100 is heated by means of its connection with a source of electrical energy, the heat is transmitted from the convolutions of the wire, through the core 1 to the wall of the fuel line 2, thereby vaporizing the fuel within the 105 line, whereby the fuel may be readily ignited at the burner, not shown. After the current passing through the wire 4 is cut off, the heat is retained within the device by means of the jacket 7 and collars 6. 110

It is to be understood that the embodiment of my invention herewith shown and described is to be taken as a preferred example of the same and that various changes in the size, shape and arrangement of parts may be resorted to without departing from the spirit of the invention as claimed.

What I claim is:

An electrical heater comprising, a heat conducting, electricity insulating core adapted to be concentrically mounted on a fuel line, a tubular jacket surrounding said core and projecting from the ends thereof, said core being formed in its periphery with a continuous thread extending circumferentially around the core in spiral formation, said jacket being formed with a pair of

openings respectively spaced from the ends thereof, a single conductor formed with a series of convolutions seated in said thread and having its end portions extending through said openings for connection with a source of electrical energy, said thread being of greater depth than the thickness of said conductor to permit expansion of the convolutions of the latter and maintain the same in spaced relation to said jacket, and means at the ends of said core and extending into the ends of said jacket and coacting with the latter to prevent the passage of heat from said core to the outer atmosphere.

In testimony whereof, I affix my signature thereto.

SAMUEL S. BOLSINGER.
